UNITED STATES PATENT OFFICE.

EMIL A. FLORANG, OF BURLINGTON, IOWA.

REFRIGERATOR BASKET.

Application filed February 8, 1924, Serial No. 691,422. Renewed October 9, 1926.

The invention has relation to refrigerator baskets, having for an object the provision of an improved basket of this description.

The invention consists in the novel construction and combinations of parts as hereinafter set forth.

In the accompanying drawings illustrating the invention, Figure 1 is a central vertical section of a basket having the invention applied thereto; Figure 2 is a plan view of the same with the cover removed; Figure 3 is an enlarged detail fragmentary sectional view with cover raised; Figure 4 is a similar view with cover closed; Figure 5 is a fragmentary sectional detail perspective view of the top edge of the basket, and Figure 6 is a fragmentary detail plan view of the top edge of the basket, partly broken away.

In these drawings the numeral 1 designates the body of the basket, woven from slab rattan and provided with a metal lining 2, an insulation being used between the rattan basket and said metal lining and consisting of corrugated asbestos board 3.

The top 4 of the basket is provided with a central portion 5, which is thicker than its marginal portion 6, the latter having a lower packing strip 8 adapted to rest upon the peripheral top edge of the basket. The metal lining 2 is provided with a peripheral outwardly extending top flange 15 resting upon horizontal peripheral top strips 14 of the basket body, and with an upwardly and inwardly directed inner peripheral hollow bead 9 of U-form in cross section, the branches of which straddle the inner corner of the inner strip 14. This bead 9 while hollow, is protected against causal injury by having its lower portion extending below the top edge of the top strips 14 of the basket body and its upper portion sloping outwardly at a low incline to the top flange 15 to which it is joined at an obtuse angle. As a result also of the lesser projection of the bead 9 above the top edge of the basket, the crack or interval between the cover 6 and the basket body is made less.

In order that the joint of the cover with the basket shall be as nearly air tight as possible, to prevent the escape of cold air from the basket, the metal lining is provided with the aforesaid bead 9 engaging the packing strip 8, and said bead is made to project not only upwardly but also horizontally inwardly of the basket to engage the shoulder 7 of the central portion of the

cover, said bead having an upwardly and outwardly rounded or tapering inner peripheral wall 9a.

As shown in Figure 1 of the drawings, as the cover is placed upon the basket, the shoulder 7 engages the bead 9 and being pressed down will closely engage the inner peripheral edge 9a of said bead in a wedging air tight manner, said wedging engagement being readily releasable by upward movement of the cover owing to the fact that the inner peripheral edge 9a of the bead has only a limited horizontal line or area of contact with said shoulder. This bead 9 of the top flange of the lining is made by running a crimping tool around the lining upon the horizontal peripheral inner edge of the basket, and is quite accurately horizontal, its engagement with the shoulder 7 of the cover being therefore the more perfect.

In forming the air space in the basket between the metal lining and the wickerwork body, the asbestos board 3 is arranged with the air spaces 12 of the corrugations thereof running in upright fashion substantially vertically peripherally at the sides of the basket, said air spaces communicating at the top thereof with a peripheral air space 13 between said lining and the horizontal peripheral inner top strip 14 of the basket body, the hollow of the bead 9 communicating with said air space and the horizontal flange 15 of said lining and of which the bead 9 forms a part, closing the air space 13 at the top.

The air spaces 12 of which there is a peripheral series around the sides of the basket, are closed at the bottom by the solid bottom 16 of the basket, and by the horizontal strip 17 of corrugated asbestos board overlying said solid bottom and underlying the bottom of the metal lining and providing horizontal air spaces 18 in series between these two bottoms.

I claim:

1. In a refrigerator basket, a body having horizontal peripheral top strips, a metal lining having a peripheral outwardly extending top flange resting upon said top strips and an upwardly and inwardly directed inner peripheral hollow bead of U-form in cross section, the branches of which straddle the inner corner of the inner of said top strips, the lower portion of said bead projecting below the top edge of said top strips and the upper portion thereof being joined to

said top flange at an obtuse angle, and a cover having a reduced marginal portion provided with a lower packing strip resting upon said bead and a thicker central portion having a vertical peripheral shoulder having wedging engagement with said bead.

2. In a refrigerator basket, a body having horizontal peripheral top strips, a metal lining having a peripheral outwardly extending top flange resting upon said top strips, and an upwardly and inwardly directed inner peripheral hollow bead of U-form in

cross section, the inner of said top strips being spaced from said lining by an air space communicating with the hollow of said bead and closed at the top of said flange, and an insulation lining located between said metal lining and the sides of the basket body and having a peripheral series of upstanding air channels communicating with said air space. ¹⁵

In testimony whereof I affix my signature.

EMIL A. FLORANG.
